UNITED STATES PATENT OFFICE

2,098,870

ROAD JOINT MACHINE

John N. Heitzel, Warren, Ohio

Application March 12, 1934, Serial No. 715,243

15 Claims. (CL. 94—45)

The present invention relates to improvements in road joint machines, having in mind certain improvements over the machine forming the subject matter of my prior Patent Number 1,740,345, granted December 17, 1929, and being a continuation in part of my co-pending applications Serial Number 414,538, filed December 16, 1929; Serial Number 555,619, filed August 6, 1931; and Serial Number 702,052, filed December 12, 1933.

10 It is an object of the present invention to produce a machine for forming traffic lines in concrete or other roadways, and involving the weighing of the cement, sand and crushed stone, as well as the measuring of the water for each batch, 15 so as to provide a consistent mix throughout the structure, including the proportioning of coloring pigment when such is required.

The invention also aims to provide an improved form of mixer and a unique method of mixing 20 the concrete, together with a tubular valve arrangement on the batcher so as to control the flow of the cement to a very accurate and minute degree.

Another object of the invention is to provide a 25 novel method of supplying, to a minute degree, the quantity of mixed traffic line material to the channel in the roadway so there will be substantially no surplus, or inadequate volume, of material positioned within the channel.

30 A further object of the invention is to provide means for roughing, or raking up, the concrete in the road slab under the traffic line installer to insure a bond of the traffic line material to the road slab.

35 A still further object of the invention is to provide means for installing joint material in the roadway adjacent to the traffic line simultaneously with the performance automatically and progressively of all of the other operations incident to road construction.

A still further object of the invention is to provide means for installing dual traffic lines in a roadway, involving concrete surfacing devices in cooperation with the installing implements.

45 With the foregoing and other objects in view, the invention will be more fully described herein-after, and will be more particularly pointed out in the claims appended hereto.

In the drawings, wherein like symbols refer to 50 like or corresponding parts throughout the several views,

Figure 1 is a perspective view, with parts broken away and parts shown in section, illustrating an improved machine constructed in accordance 55 with the present invention.

Figure 2 is a perspective view of the weighing device.

Figure 3 is an enlarged sectional view of the improved form of valve.

Figure 4 is a vertical section showing a form of 5 tire and wheel used.

Figure 5 is a fragmentary perspective view showing an improved joint construction in the road.

Figure 6 is a longitudinal section of one of the 10 operating devices.

Figure 7 is a fragmentary perspective view, with parts shown in section, of a device for installing traffic line material by hand.

Figure 8 is a fragmentary perspective view, 15 with parts shown in section, illustrating a side form combined with a deformed steel strip.

Figure 9 is a cross section taken through the deformed steel strip.

Figure 10 is a fragmentary perspective view, 20 with parts broken away and parts in section showing a traffic line installing device operating under a screed.

Figure 11 shows a section of concrete road material with a modified form of traffic line joint. 25

Figure 12 shows a further modified form of apparatus.

Figure 13 is a perspective view of a further modified form of depositing device.

Figure 14 is a vertical sectional view showing 30 a modified form of tubular valve member.

Figure 15 is a fragmentary perspective view, with parts shown in section, of the two valves and associated parts.

Figure 16 is a cross section through a road 35 construction showing a corrugated or roughened traffic line, and

Figure 17 is a similar view showing a modified form of corrugated or roughened traffic line.

Referring more particularly to the drawings, 40 20 designates a section of the concrete or other roadway which has already been constructed, the traffic line 21 and the joint 22 having been completed.

At 23 is shown a second section of roadway 45 which is in the course of construction adjacent to the slab 20; and 24 represents dowel bars, which have been previously installed in the slab 20, and project therefrom in order also to be received within the new slab 23 to tie the slabs 50 20 and 23 together. These dowel bars may be installed in accordance with the methods described in my application above referred to, Serial Number 702,052.

Referring more particularly to the machine 55

for performing the various operations, 25 designates generally the frame of such machine. This frame spans the roadway and is mounted for longitudinal movement over the roadway by means of double flanged wheels 26, which operate on the side forms 27, and the special form of pneumatic tired wheels 28 at the opposite side of the machine, which pneumatic tired wheels roll directly on the surface of the hardened or 10 semi-hardened slab 20.

This form of pneumatic tired wheel is more particularly shown in Figure 4, and is so constructed and adapted as to travel, and permit the support of a considerable load, on concrete 15 that has not sufficiently hardened to permit the use of a steel wheel thereon, and where even a hard rubber wheel might not be found to possess sufficient resiliency to avoid marring the recently laid concrete slab. The rim of the new 20 form of wheel is designated at 29, the same being mounted on the axle 30. A shoe 28 is mounted on the rim 29 and contains an inner tube 31. The shoe 28 is constructed with a central inwardly projecting ring portion 32 which may be 25 solid with the outer portion of the shoe 28 and acts to prevent the complete flattening of the tire when such ring portion 32 engages the rim 29, as shown in the lower portion of Figure 4, where the ring portion 32 provides for the limitation 30 of the flattening of the tire, which flattening might be caused by either overload or insufficient air pressure. In case of puncture or blow out, the ring portion 32 will take up the load and prevent the complete flattening of the 35 tire and tube 31, thereby avoiding the load from being absorbed by the outermost flange portions 33 of the rim 29.

It will be understood that the tire, when only slightly inflated will have greater traction than 40 ordinary vehicle tires requiring much greater inflation, and the ring portion 32, when absorbing at least a part of the load, will prevent the breaking down of the fibers in the body of the tire casing 28. This special tire construction 45 may be used in connection with other vehicles, and may be found practical for use in connection with automobiles to avoid sudden deflation of the tire in the event of puncture or blow out, so that the improved form of tire will contribute 50 considerably to the safety of automobiles should blow outs occur when operating at a high rate of speed.

At the rear portion of the frame 25 of the machine is located a transverse joint cutter 34 55 suspended by adjusting screws 35, or other appropriate devices. The transverse joint cutter produces the transverse joint 36 in the slab 28.

It will be understood that the concrete has 60 been previously poured and surfaced, and that a groove or separation 37 and a depression or channel 38 has been formed in the plastic concrete by elements attached to the finishing machine, as described in my co-pending application Serial No. 702,052, and temporary cover 65 plates 39 have been inserted to prevent concrete entering the channel during the surfacing of the concrete, and during the longitudinal floating operation, as performed by the float member 40. Such float member has a handle 41, or other 70 suitable means, for operating the same to float or surface over the transverse joint produced in the concrete by the blade 34. After the surfacing has been completed, the cover plates 39 are lifted by workmen operating from the extended 75 platform 42.

The machine herein described follows as closely as practical rearwardly of the finishing machine. The present machine is driven by a motor 43. Through a chain and sprocket mechanism 44, the motor 43 drives the front shaft 45; and through chain and sprocket mechanisms 46 and 47, the front shaft 45 drives the rear shaft 48. These shafts 45 and 48 contain the wheels 26 and 28.

There is a traffic line material forming and 10 volume-gauging member 49, being of substantially channel shape, and having a joint producing flange 50, which moves in the plastic concrete of the roadway and extends substantially the full length of the member 49 on one side thereof, and 15 on the other side of such channel member 49 is a substantially shallow flange 51. Both flanges penetrate the material of the surface of the roadway. In front of the channel member is a block 52 to reform the depression 37 to the required 20 depth as may be necessary to receive traffic line material 53. Such material is supplied by the hopper 54. It will be understood that the weight of the traffic line material 53 will exert a pressure 25 on the traffic line material as it moves through the opening in the bottom of the hopper and is projected under the traffic line former 49.

A material proportioning and mixing apparatus is provided on the machine for accurately proportioning the materials for each batch to be 30 mixed either by volume or weight. The bin 55, which may be of suitable size, contains a number of compartments, for instance, the compartment 56 for the cement, 57 for coloring pigment, 58 for sand, and 59 for the stone. If desired, each of 35 these compartments may be of actual size as may be required for a complete batch, that is, assuming that one complete batch would consist of one part cement, two parts sand, and three parts stone, these compartments 56, 58 and 59 may be 40 of a capacity relatively to contain such volumes of material. It will be understood that the water ratio is also proportioned by the capacity of the container 60.

The material, when batched either by volume 45 or weight, is projected into a pugmill, or other mixer, having the trough 61 of semi-circular form, open at its top. In the trough is a shaft 62 driven by chain and sprocket 63 from the motor 43. The shaft 62 is provided with agitating fingers 64. 50 After the mix has been completed, the same is dumped into the chute 65, which is located under the mixer. The dumping of the material is accomplished by rotating the mixer barrel 61 on the shaft 62, whereby the material is conveyed to 55 the supply hopper 54.

If desired, the materials may be weighed instead of batched by volume.

Below the hopper 27 is a weighing batcher 66 having compartments 67, 68, and 69 for stone, 60 sand and cement respectively. An automatic dial 70 is mounted in connection with the weighing batcher 66 for indicating the correct proportion of the materials by weight. The flow of stone and sand is controlled by the sliding gates 71 and 72 at the bottom of the compartments of the bin 65.

The correct amount of cement is discharged from the bottom of compartment 66 into the cement compartment 69 of the batcher and 70 weighed. The correct quantity of water for each batch is predetermined and held in the container 60.

I have discovered a unique method of mixing the concrete to produce a higher strength con- 75

crete than was possible heretofore in the old method of permitting the sand to contact the stone aggregate which has always caused a film or insulation to be created on the surface of the stone.

5 According to my method, higher strength concrete is produced by first depositing the accurately-proportioned cement and water into the mixer, thus producing a cement sludge, and then dumping an accurately-proportioned amount of stone 10 into the sludge to cause coating of the stone; thereupon dumping an accurately-proportioned amount of sand into the mixer and mixing with the mass.

The proportioning of the cement is a very important operation because of the high cost of this class of material. In order to provide a highly accurate control of the cement from the bin to the weighing hopper, I provide a specially designed flexible tubular valve 13, shown more particularly in Figure 3. This valve is connected at the bottom of the cement compartment 56, and is found to be most efficient when made of rubber, although it may be constructed of canvas or any other suitable material. Such tubular valve is 20 opened and closed by roller members 14 and 15, which are moved toward and from one another by a handle or lever 16 and any appropriate linkage.

The compressing of the rubber valve 13 between 30 the rollers 14 and 15 will close off the flow of cement. When the proper quantity of cement has been projected through the valve into the compartment batcher weigher 69, such weight is registered on the dial scale 70 and such valve is 35 thereupon tightly closed. An emergency slide gate 71 is provided at the bottom of the compartment 56 for closing off the flow of material into the tubular valve 13. In Figure 3, the cement is shown in the tubular valve, the valve being in a 40 closed position with the rollers 14 and 15 brought together.

It will be noted that the lower portion of the valve, below the rollers 14 and 15, contains a quantity of cement, which cement is regulated in 45 its discharge by the single roller cut-off member 18 suspended from an arm 79 and operable by means of the handle 80. The cut-off roller 18 is shown in partially open position. The object 50 of this cut-off roller 18 is to provide means for enabling the projecting of the final amount of cement into the batcher, it being understood that cement oftentimes sticks in the bin, and, when the volume of cement breaks away, such adhering cement would be apt to drop through the valve 55 and produce an overweight. Therefore, the cut-off roller 18 controls a considerable final quantity of cement in the tubular valve 13 above such cut-off roller.

While the two valve rollers 14 and 15 effectively 60 shut-off the further descent of any cement from above them, the lower cut-off roller 18 may be so adjusted as to regulate the issuance of the final quantity of cement into the batcher so that the balance on the scale 70 may be nicely arrived at. 65 This final quantity of cement required will be projected through the bottom of the tubular valve 13 by manipulating the lever 80. It will be understood that a portion of the cement above the roller 18 will be retained in the flexible or tubular valve 13 until the next batch is required, and thereupon the operation is repeated by manipulating both of the levers 16 and 80 to permit the cement to flow rapidly through the tubular valve 13 until the great majority of the required quantity of cement is registered on the scale. At

this time, both levers 16 and 80 may be brought into a closed position choking the tubular valve 13 substantially as indicated, and in particular closing off the top valve against the flow of any material whatsoever. By manipulating the lower 5 lever 80, the pressure of the roller 18 may be gradually released and the roller moved toward the right whereby to open the throat of the valve to a restricted extent sufficient to allow such portion of the final quantity of cement to descend 10 as is necessary to tip the scale to the predetermined point.

It is a well-known fact that cement when exposed to dampness cakes or slightly sets, so that it becomes necessary to break up the lumps. It 15 was found in the old type of valves that this caking of the cement would clog the valve and there was no means of breaking up the lumps. However, with the improved form of tubular valve 13, it is possible to break up the lumps of cement 20 which accumulated in the valve by manipulating both of the levers 16 and 80. Any lumps of cement that would tend to choke the valves are very readily crushed and therefore easily passed through the valve. In order to provide access to 25 the valve chamber, I provide inspection doors 81 in the casing on each side of the valve 13.

At one side of the machine is provided a traffic line installing device, which is useful for installing traffic lines on four lane traffic highways. The 30 traffic line is designated at 82 and the traffic line forming member at 83. Such traffic line member 83 is similar to the member 49 with the exception that both depending flanges of the channel are of equal and very slight depth. The deep flange 35 50 of the channel member 49 is not required in connection with the forming of traffic lines adjacent to a previously constructed slab, such as the slab 20.

The hopper member 84 is secured to the frame 40 25 of the machine, and is adjustable as to position by the hand wheels 85. The forward end of the member 83 is curved up as indicated at 86.

It will be noted that the transverse surfacer 87 operates over both members 49 and 83. It will be 45 also noted that in the rear of the machine, the hand float 88 is manipulated manually over the member 83.

As shown in Figure 6, the forward portion of the reforming member 49 is solid from the opening at the base of the hopper 54 up to the forward end of the member and this block member is designated at 52. This construction requires that the traffic line material 53 will move downwardly through the opening at the base of the 55 hopper 54 and be projected back into the space under the member 49 in a progressive manner as the machine is moved forward. Therefore, there is no surplus of traffic line material, only enough being supplied to completely fill out the 60 section of traffic line as indicated at 89. This traffic line 89 is formed simultaneously as the joint material 90 is moved into the plastic concrete from the wheel 91 carried on the forward portion of the machine. This wheel or spool 91 contains 65 flexible joint material, which may consist of very thin paper, or "Cellophane", or other suitable material, such as burlap or a very thin grade of cotton fabric.

It will be understood that it is not necessary in 70 all instances to use ribbon joint material, as indicated at 90 and 91. Instead of using such a ribbon joint, sand, oil, or other suitable material, which will prevent amalgamation of the concrete, may be projected along the line of the joint 75

or along the blade 50, which will prevent the amalgamation of the concrete and thereby form a plane of weakness as indicated at 90.

In order to control the alignment and elevation 5 of the member 49, the hopper 54 is securely welded or otherwise joined to the member 49. The hand wheels 92 are provided for adjusting the hopper 54 and the member 49 to the proper elevation and securing same in position so as to produce a 10 pressure on the traffic line material when so required, preventing the member 49 from raising up out of position.

Forwardly of the member 49 is an eccentric 93 secured to rotate with the shaft 48 and having a 15 link 94 extending back and pivoted, as indicated at 85 in Figures 1 and 6, to the forward portion of the member 49 or its block 52. The eccentric causes longitudinal reciprocation of the members 49 and 52 through a slight range of movement 20 which reciprocation will cause the traffic line material 53 to be compacted and surfaced.

To further compact the material, an electric or other suitable vibrating means 96 is attached to the member 49 whereby to vibrate said member 49 as well as to communicate vibration to the hopper 54, which will tend to project the traffic line material 53 down into the hopper and under the member 49.

The members 49 and 52 are pivotally supported 30 from the transverse beams 97 and 98, through the lower ends of the adjusting screws 92 being pivoted, as indicated at 99, to the beam 97 and the adjusting screw 100 for the block 52 being pivoted, as indicated at 101, to the forward beam 98.

The two rear adjusting screws 92 are also pivoted to the hopper 54, as indicated at 102. When it is desired to raise the hopper 54 together with the forming member 49, it is only necessary to 40 manipulate the adjusting wheels 92 for up or down movement. The surfacing members 87 and 103 reciprocate transversely over the members 49 and 52 progressively as the machine moves forward. This reciprocation is accomplished by 45 the arms 104 and 105 pivoted respectively to the surfacers 87 and 103, and being pivoted in turn to opposite ends of a walking beam 106, which walking beam is pivoted centrally, as shown at 107, to the transverse beam 97. A pin 108 on 50 the walking beam fits into a spiral groove of a cam 109 fixed upon the power shaft 110. The two surfacing members 87 and 103 are thereby given a lateral reciprocation, the same being out of step with one another. The surfacing members 87 and 103, as shown in Figure 6, operate over the members 49 and 52 and do not come into contact with the installed traffic line material 53, which material issues out of the rear end of 55 the member 49.

60 Referring more particularly to Figure 7, there is here illustrated a hand device for installing traffic line material. In this figure, 111 represents the concrete slab, and 112 the traffic line material. A channel shaped forming member 65 113 is provided with a groove cutting element or blade 114, and such member is flared up or rounded at each end, as indicated at 115, so that the implement may be reciprocated backward and forward by use of the hand gripping handle 116.

70 On the member 113, either welded or otherwise secured to the top surface thereof, is a hopper 117 and an electric vibrator 118 may be mounted on the hopper if desired. At 119 is indicated a valve for controlling the flow of material out 75 of the hopper, which valve is positioned for ma-

nipulation by the hand which engages the handle 116.

The hopper contains traffic line material, which may consist of white cement, or pigment of the desired kind. Such material is carried in suitable quantities in the hopper 117, and such material is projected under the member 113 as released by the valve 119, which valve is manipulated by the hand.

Referring more particularly to Figure 5, such figure represents a sectional view of a longitudinal joint 90a, similar to the joint 90 described in the process of installation in Figure 1. This joint, as previously stated, may consist of a very thin material such as "Cellophane", burlap, or thin cotton fabric, the material also being preferably extremely pliable and which when installed will have no resistance to the lateral thrust of the coarse aggregate, so that the coarse aggregate, such as stone, gravel or sand, will tend to deform the joint material as indicated, thereby creating an irregular surface adjacent this joint strip. In such way, there is provided a roughened surface for substantially the full depth of the slab, as indicated. The joint strip 90a projects for approximately three inches into the concrete causing an irregular crack 120 to develop in the bottom portion of the slab. The transverse joint, which transverse joint was indicated by the numeral 36 in Figure 1, consists 30 of a groove 121 in the lower portion of which is placed a filler 122 of low melting point asphalt, or in other words, a very soft grade of asphalt or tar which will remain flexible or soft at all times regardless of cold weather. Above this 35 filler there is placed a mass 123 of high melting point asphalt or other desired material, which will remain hard during high temperatures, thus preventing the material from running or flowing from the joint during the hot weather. This is 40 important inasmuch as it has been found that, when grooves are completely filled with a high melting point material, the filler material cracks in the winter and permits water to flow through the crack down into the subgrade of the roadway; whereas when filled with a soft material, it has been found that traffic will pick up the soft material and distribute it over the roadway, 45 thereby disfiguring the surface of the road.

Referring again to Figure 6, the member 49 is 50 shown with the joint cutting blade 50. This blade 50 penetrates to an appropriate depth of approximately three inches. The block, 52 creates a void back of the same, so that the top of the channel member 49 is spaced above this void 55 or depression and there is produced a hollow space to receive the material 53. The member 52 will form a comparatively smooth channel, that is, the channel will have a comparatively smooth surface at the bottom.

In order to roughen the surface, I provide a finger or rake member 124, which projects down into the channel and roughens or routs the bottom of the channel and the traffic line material. The void under the surface of the member 49 is 65 completely filled with traffic line material and tamped into place by operating the vibrating member 96. Simultaneously, the transverse surfacing members 87 and 103 may be operated over the top surface of the installing member. The 70 longitudinal joint or grooving blade 50 forms the groove or separation along the joint, and in order to further compact the material, the longitudinal member 49 may be reciprocated by the eccentric 93.

Referring more particularly to Figure 8, instead of producing a transverse groove by the blade 34, it may be desired in some instances to produce a tongue and groove joint, and for this purpose, an angular shaped or deformed steel strip 125 may be inserted through slots 126 in the webs of the side forms 127. Such strip 125 extends completely across the roadway substantially in the center of the thickness of the concrete, it being understood that the concrete is poured around the strip, and after the concrete has been finished and before it has taken its initial set, the strip 125 is pulled out longitudinally by the hook member 128. In this way, a separation 129 will be left in the body of the slab, such separation inducing a crack to develop in that portion of the slab below, as well as that portion of the slab above, such separation.

In order to prevent a ragged crack in the top surface of the slab above the separation 129, a groove 130 of slight depth is produced in the top portion of the slab by lowering the cutter 34 down into contact with the concrete and producing an incision which may be later finished with a hand grooving tool.

In order to insure a complete separation of the concrete adjacent to the tongue and groove, the removable strip 125 may be coated with heavy oil, soft asphalt, tar or the like. Such coating will assist in reducing the friction incident to the withdrawal of the strip. The oil or tar will adhere to the concrete, so that the strip 125 may be withdrawn while the concrete is extremely plastic, allowing the tongue and groove to completely close up; in other words, allowing the walls of the concrete to slump completely together.

Instead of using oil or asphalt for the strip 125, it may be advisable, in some instances, to use a very thin paper strip 131, such as shown in Figure 9. This thin paper strip 131 may be folded against the member 125, and the concrete poured around same, whereby, when withdrawing the strip 125, the paper 131 will remain in position.

In some instances, it may be required that the paper strip completely surround the member 125 to keep such member entirely from contact with the concrete, to the end that an easier withdrawal of the strip 125 may be had.

Referring more particularly to Figure 13, 132 designates a modified form of depositing member to take the place of the member 49. Such member is supported and carried by the cross beams 98 of the carriage or frame of a travelling bridge or finishing machine well-known in the art.

The longitudinal member 132 is substantially channel shape in cross section, having a filler block 133 positioned within the channel at the forward end to produce the groove or the depression in the surface of the plastic concrete, which receives the traffic line material. A screed or other surfacing member 134 reciprocates transversely over the block 133.

Means are provided for vibrating the surfacing member 134 and the channelling member progressively as the screed or surfacing member reciprocates transversely. A corrugated or notched member 135 is formed, or attached to, the screed or surfacing member 134. The length of this member 135 may be the full length of the screed if so desired. One or more rollers 136 rest on the notched strip 135, such rollers being attached to spring arms 137, which arms are urged downwardly by spring pressure and are

attached to the frame member 98. Such spring will produce a downward thrust on the roller 136, so that when the screed is reciprocated, the roller will drop into the corrugations or notches and produce hammer blows or vibrations to the surface. The forward end of the member 132 is secured to the carriage and arranged for vertical and lateral adjustment by the hand wheels 138.

It will be understood that, as the machine moves forward, the channelling member 133 will produce a channel which is substantially smooth. In order to secure a bond of the traffic line material within the channel, a roughening device is provided. This device may consist of a shaft 139 having rake teeth 140. The shaft is rotatably mounted above an opening in the member 132, being journaled in side plates 141, one of which constitutes a perforated quadrant 142, to receive the pin latching device 143 carried by the handle or lever 144 which is affixed to the shaft 139.

As the machine moves forward, the rakes 140 rout up the concrete, or roughen it, to the extent desired. It will be understood that the opening to admit the roughening members also provides a means for inspecting the groove formed by the member 133. When it is desired to withdraw the roughening member from contact with the concrete, the lever 144 is swung around. Thereupon the latch device 143 may engage one of the notches 142 in the quadrant to hold the device in the adjusted position.

Following the roughing of the bottom of the channel, traffic line material may be introduced through the hopper member 145. To prevent the roughened material produced by the rake 140 from projecting above the top surface of the traffic line material, a depressing member 146 is provided to depress the roughened bottom of the channel or groove. A gate 147 at the bottom of the hopper enables the operator to shut off the flow of traffic line material whenever desired.

In order to inspect the installed traffic line material progressively as the machine moves forward, an opening 148 is provided in the top of the member 132. This opening will facilitate the release of air, which might be confined under the member 132.

Above this opening are provided upstanding flanges or walls 149 to provide for the accumulation of surplus traffic line material so as to fill any voids which might develop during the process of installation.

As heretofore described, sand may be used as a joint material to which end there is supplied a sand receptacle 150. This receptacle communicates at its bottom with the space alongside the joint grooving blade 151 whereby to distribute sand along the joint groove. In lieu of using sand as joint material, it may be desirable in some cases to use removable steel joint plates 152, which are positioned along the blade 151 progressively as the machine moves forward, the blade 151 serving as an aligning member for the strips 152. One of these installed strips is indicated at 152a. Such strips may be removed if desired, or they may be left in place. Should it be desired, the strips may be removed and the resulting groove filled with a suitable filler material.

In order to surface the top of the concrete slab along the edge of the traffic line, I provide side extensions 153. These extensions produce rounded edges along the traffic line to prevent raveling or chipping. Companion adjusting screws 138 and 134 are supplied at both the forward and

rear ends of the member 132 whereby that member may be adjusted vertically, and whereby also the member may be adjusted and securely positioned on the top surface of the road so as to 5 equalize the pressure.

Referring more particularly to Figure 16, 155 represents the concrete slab and 156 represents the corrugated or roughened cement traffic line edge. It is understood that, when white cement 10 is corrugated on the top surface, it will cause the reflection of light rays, thus emphasizing the traffic line, particularly at night under the illumination of vehicle headlights. The roughened or corrugated surface 156 also prevents slippage 15 of vehicles when moving on the traffic line.

Referring to Figure 17, the traffic line is formed of a corrugated plate or strip 157 made of steel or other suitable material, preferably of a non-corrosive metal. The strip has a joint forming 20 portion 158 with dowel members 159 passing therethrough. The dowel members provide a means to prevent the separation of the slabs, and also serve to retain the strips 157 in contact with the roadway. On each side of the traffic line 25 strip, small grooves 160 are formed which are later poured or sealed with a bituminous material to prevent water or foreign matter from moving under the strip 157. The edges of the strip are turned down as indicated by the depending lips 30 161 to reinforce the strip along its edges.

Referring more particularly to Figure 14, 162 designates the main bin containing cement, sand or other road building materials, as indicated at 35 163. It is well known in the handling of materials, particularly cement and sand, that such material bridges or arches as indicated at 164, so that material will not flow. It is necessary in such cases to agitate the material by vibrating the bin, or injecting air into the material. In 40 order to break the arching of the material, I provide one or more springing plates 165, which are secured to the sides of the bin at preferably their upper edges, by welding, bolting, riveting, or the like, so that the weight of the material 163 will 45 depress the plates 165; or in other words, spring the plates downward.

As a rule, it has been found that the recoil of the spring plates 165, causing such plates to move upwardly and downwardly, will cause the material to be distorted, so that the arching of the material will be broken, as indicated at 166.

One or all of the spring plates or baffles 165 may be vibrated as desirable. To this end, I provide a means for vibrating the plate by projecting 50 55 a plunger 167 through the wall of the main bin 162 in position to contact the spring plate 165.

This plunger has a reciprocating movement through the opening in the bin wall. In order to vibrate the plunger 167, I provide a lever 168 pivoted, as indicated at 169, to the bin or some other appropriate support and carrying a hammer 170 located and positioned to engage the plunger 167. The impact of the hammer 170 on the plunger 167 will cause vibration of the baffle 60 65 plate 165 with the result that the arching of the material 163 in the bin will be broken down and such material will flow freely.

Below the bin are located one or more tubular valves 171 having the roller members 172 and 173 70 at opposite sides thereof for pinching the tube 171, as illustrated to close off the flow of the material downwardly through said tube and into the mixer or weighing device. In Figure 14, the roller members 172 and 173 are in closed position. These rollers 172 and 173 are mounted on arms 75

174 and 175 pivoted at 176 and 177 on appropriate parts of the framework. In the closed position of the valve, the arms 174 and 175 extend upwardly and converge toward one another from the pivot points 176 and 177. Consequently, the rollers 172 and 173 are raised in order to open the valve, and are lowered to close the valve. In the closed position illustrated, the weight of the material in the tube and bin is exerted on the rollers 172 and 173 tending to 10 cause the rollers to descend and thus move closer together, whereby the effect is to automatically close the valve and maintain the valve in closed position, until, by manual action, the rollers 172 15 and 173 are positively raised.

This raising of the rollers may be accomplished by a lever 178 pivoted to the framework, as indicated at 179, and connected with the arm 174 by a link 180. The arms 174 and 175 may be bell-cranks with angular branches 181 and 182 20 extending in relatively opposite directions with respect to the pivot points and being coupled together by a link 183 whereby to simultaneously actuate the arms and the rollers 172 and 173 mutually toward and from one another. Of course, 25 any other arrangement of levers may be substituted, but the arrangement shown will accomplish the purpose of moving both rollers 172 and 173 at the same time, in relatively opposite directions, and the arrangement also permits of 30 the effective closing of the valve and the automatic tight shut-off of any seepage of material therethrough.

Referring more particularly to Figure 15, there is here illustrated a plurality of valve members 35 184 and 185, which may both be disposed beneath the same bin, for instance such as the bin shown at 162 in Figure 14, the plurality of tubular valves being substituted for the single tubular valve of Figure 14. It may be desirable in some cases 40 to utilize a plurality of tubular valves which may be of smaller diameter than a single large valve, the advantage being that, where a plurality of smaller tubular valves are used, a large volume of materials may be projected through the plural 45 tubular valves at the same time, and then one of the valves may be closed off and a final quantity of materials may be gradually projected through the single valve to complete the weighing or proportioning operation. Pairs of rollers 186, 187, 50 188 and 189 cooperate independently in pairs to pinch individually either of the tubular valves 184 and 185 whereby, when one of the tubes is shut off, the flow through the other may be restricted only to allow the passage of the final 55 quantity of cement necessary to tip the scales.

Referring more particularly to Figure 10, this figure embodies a construction forming a continuation of my co-pending application, Serial No. 343,991, filed March 2, 1929, for Joint installing machine. More particularly Figure 10 herein embodies Figure 11 of that co-pending application.

In this Figure 10, there is illustrated a transverse joint installing device associated with a 65 reciprocating screed 190 of a road finishing machine which may operate in advance of the longitudinal joint installing apparatus. The screed 190 has the front wall 191 and the rear wall 192, said front wall pushing the surplus material 70 ahead of the screed. The screed is moved rearwardly from the surplus material for the installation of the transverse joint.

The walls 191 and 192 are connected by yokes 75 193, only one of which is shown, and each yoke

is pivoted to the lower end of a rod 194 of the finishing machine, said rod being pressed downwardly by a spring 195, to hold the screed on the side rails or forms.

5 The screed is reciprocated and a push rod 196 of the machine has rollers 197 bearing against the wall 191 and the bottom of the screed, for pushing the screed forwardly with the machine.

The joint installing blade or mandrel 198 is located in rear of the screed and is movable within an overhanging portion 199 of each yoke 193, a screw 200 being threaded through a nut 201 trunnioned within the portion 199 and having its lower end connected by a swivel and universal 15 joint 202 with the blade 198, to permit the blade to be reciprocated longitudinally.

The screws 200 may be rotated for raising and lowering the blade. An arm 203 is hinged to the wall 192 of the screed to be swung rearwardly 20 into a cut-out portion 204 of the blade 198, in order that, when the screed is reciprocated, the arm 203 will strike the ends or shoulders of the cut-out portion 204, thereby reciprocating the blade 198. The arm 203 may be swung forwardly 25 over the screed when the blade is raised.

In operation, when the joint installing blade 198 is at the proper location, the forward movement of the screed 190 is stopped, and by rotating the screws 200 the blade will be forced down into 30 the concrete. In order to agitate the blade, a hand tamper may be used to tamp the blade, or the arm 203 may be swung into the portion or recess 204 of the blade, so as to reciprocate the blade during downward movement into the concrete.

35 The blade will thus move into the concrete with a sawing action as the blade is moved downwardly by the screws.

The blade may be used for producing a cut 40 or groove in the concrete, or a V-shaped joint strip or form 205 may be placed on the blade before it is depressed, so as to be deposited in the concrete, said strip remaining in the concrete when the blade is raised. After the blade is raised 45 above the concrete, the screed is then raised from the concrete and the machine backed up to bring the screed over the joint strip or member, and the screed is then let down on the concrete and is reciprocated over the joint strip or member 50 to bring said strip or member flush with the surface of the concrete and to finish the concrete adjacent to the joint.

The joint member may be of a V-shaped form, as shown, to be removed subsequently and the 55 groove filled with suitable sealing material, or the joint member may be of suitable premolded joint material to remain in the concrete.

Referring further to Figure 10, 206 represents 60 a traffic line installing apparatus or member, which operates under the screed and which in detail is very similar to the traffic line channeling and grooving device heretofore illustrated and described.

In connection with this member 206 I provide 65 a paper folding device including a channel shaped member 207 having a closed top portion with depending flanges 208. The paper, indicated at 209, is passed through the member 207 and is shaped and formed thereby as indicated at 210. The 70 paper member 210 will form a separation in the concrete and the top portion of the paper will form a temporary protecting cover to the installed traffic line material 211. The roll of flat paper 209 is supported on the top of the channelling member 206, it being understood that the chan-

neling member is secured to a finishing machine or travelling bridge. Hand wheels 212 are secured to the adjusting screws 213 which are in turn secured to the travelling bridge or finishing machine for up and down movement in and out the 5 plastic material.

A material hopper 214 is arranged to receive traffic line material, which passes through the bottom of the hopper and moves into the channel 206. As it emerges at the opposite end of the 10 installer, as indicated at 211, and progressively as the machine moves forward, the paper strip 209 is unrolled from the reel and deformed by the deforming member 207.

The deformed strip 210 is more clearly indicated in Figure 11 in which the top portion forms 15 a separation in the concrete.

The temporary top protector portion of the deformed strip 210 will protect the top surface of the traffic line material 211. It will be noted 20 that the slight depending portion 218 of the traffic line material projects into the concrete only enough to secure the protector strip to the surface of the road temporarily. After the concrete has finally cured and hardened, the top of the 25 strip 210 is torn away, as indicated at 215, in Figure 11, it being understood that the forward portion of the channelling member 206 produces the channel in the roadway indicated at 216 also in Figure 11. 30

There is a transverse surfacing member 217 which is reciprocated transversely across the roadway to surface the plastic material. It is understood that a final surfacing operation may be performed by hand or other means over the 35 protector strip 210. Such a final finishing in some instances may be required. Therefore it will be understood that the protector strip 210 will protect the white concrete traffic line 211 from disfiguration during such a final finishing 40 process.

Referring to Figure 12, 219 designates a tubular member having an inlet hopper 220 through which emulsion, asphalt, tar, or other suitable material for the producing of traffic line or a 45 joint, is moved to be disposed in the concrete slab as indicated at 221. It may be required in some instances to protect the top surface of the concrete from being disfigured by the emulsified asphalt or other traffic line or joint material. 50 To prevent this, a deformed paper cap 222 is moved into the plastic concrete over the installed material 221. The cap is deformed by the member 223 which is welded or otherwise secured to the joint member 219. The roll of material 224 55 is moved from the reel and passed progressively through the deforming member 223 as the machine is moved forward, and simultaneously if desired the transverse surfacing member 225 is reciprocated over the surface of the plastic material 222, it being understood that the protector strip 222 will prevent the emulsified asphalt or other joint material from oozing out of the crack which might otherwise be the case resulting in marring 60 the surface of the concrete.

It is understood that the apparatus is secured in an adjustable position to a finishing machine or travelling bridge by means indicated at 226, which means provide for the up and down adjustment and for otherwise securing the material to the machine for movement over the roadway.

It will be obvious that various changes may be made in the construction, combination and arrangement of parts which could be used without 75

departing from the spirit of my invention, and I do not mean to limit the invention to such details except as particularly pointed out in the claims.

Having thus described my invention, what I claim and desire to secure by Letters Patent of the United States is:—

1. In a traffic line device for roads, a depression forming member, a traffic line former behind said depression former, means between the two formers for holding a quantity of traffic line material to be delivered into the depression and molded by said traffic line former, and means acting behind the depression former for roughening the bottom surface of the groove.
- 15 2. In a traffic line device, a depression former, a hollow traffic line former trailed behind the depression former, means between the formers for holding a supply of traffic line material to be delivered to the depression behind said first former and within the second former, a carriage movable forwardly and supporting said formers, and means for subjecting the formers to reciprocating movement in the longitudinal direction in which the traffic line is being formed, said reciprocating movement being relative to and independent of the forward movement of the carriage.
- 30 3. In a machine for forming transverse joints in roads, a screed reciprocating transversely of the roadway, a transverse joint-forming member alongside said screed, means to suspend said member from the screed, and means between the screed and member for causing the member to partake of the reciprocating movement of the screed laterally across the roadway while said member is in the concrete.
- 35 4. In a machine for forming transverse joints in roads, a screed reciprocating transversely of the roadway and having front and rear walls, an arm hinged to the rear screed wall, a joint-forming member having a slot to loosely receive said arm, and universal adjusting means to suspend the member from the screed and to move the member up and down in relation to the road.
- 40 5. In a machine for forming transverse joints in roads, a screed reciprocating transversely of the roadway and having a front wall and bottom portion, means engaging the front wall and bottom portion to hold the screed down on the road and to thrust the screed forwards, a transverse joint-forming member back of and parallel to the screed, universally-mounted adjusting means to support the member from the screed, a loose connection between the screed and member to cause the member to reciprocate with the screed but through a smaller amplitude of movement, and a traffic line installer longitudinally of the roadway beneath the screed.
- 45 6. In a machine for forming longitudinal traffic line in roadways, a channelling member, a forming member trailed behind the channelling member, means to introduce traffic line material within the forming member into the channel produced by the channelling member, and a passing forming member behind the first forming member to receive a paper strip and form same into an inverted channel at the same time introducing said strip across the top of the traffic line material and down at the sides thereof.
- 50 7. The herein described method of forming traffic line in roads, which consists in channelling the plastic concrete, filling traffic line material in the channel, introducing a covering strip over and at the sides of the traffic line material, finishing over the strip and over the con-

crete roadway adjacent the strip, and subsequently removing the top portion of the strip to reveal the traffic line.

8. A device of the character described comprising a depression former adapted to move in plastic concrete for furrowing a groove therein, means behind the former for introducing joint material to the groove, a hollow former behind the first former for compacting the material into the groove, means projecting into the groove for roughening the bottom of the groove, and means to reciprocate said formers.

9. A device for forming traffic lines in plastic roadways comprising a carriage movable along the roadway, a depression former movable with the carriage and suspended for relative movement to the carriage, and means for communicating to said former a reciprocating movement on said suspension means relatively to the carriage and in addition to the forward movement of the carriage.

10. A device for forming traffic lines in plastic roadways comprising a carriage movable along the roadway, a depression former movable with the carriage and suspended for relative movement to the carriage, means for communicating to said former a reciprocating movement on said suspension means relatively to the carriage and in addition to the forward movement of the carriage, a device to introduce traffic line material behind said former, and an inverted channel-shaped traffic line former following and reciprocating with said depression former.

11. A device for forming traffic lines in plastic roadways comprising a carriage movable along the roadway, a depression former movable with the carriage and suspended for relative movement to the carriage, means for communicating to said former a reciprocating movement on said suspension means relatively to the carriage and in addition to the forward movement of the carriage, a device to introduce traffic line material behind said former, an inverted channel-shaped traffic line former following and reciprocating with said depression former, a laterally reciprocating screed mounted over said depression former, and a laterally reciprocating screed mounted over said inverted channel former.

12. In a machine for forming transverse joints in roads, a screed reciprocating transversely of the roadway and having a front wall and a bottom portion, means engaging the front wall and bottom portion to hold the screed down on the road and to thrust the screed forwards, a transverse joint-forming member back of and substantially parallel to the screed, universally-mounted adjusting means to support the member from the screed, and a loose connection between the screed and member to cause the member to reciprocate with the screed and through a smaller amplitude of movement.

13. In a machine for forming transverse joints in roads, a screed reciprocating transversely of the roadway, a transverse joint-forming member back of and substantially parallel to the screed, a loose connection between the screed and member to cause the member to reciprocate with the screed but through a smaller amplitude of movement, adjusting means on the screed for suspending and adjusting the member therefrom, said adjusting means having a lost motion connection between the screed and member for allowing of the difference in amplitude of movement.

14. In a machine for forming transverse joints

in roads, a screed reciprocating transversely of the roadway and having a front wall and a bottom portion, means engaging the front wall and bottom portion to hold the screed down on the road and to force the screed forwards.

5 15. In a machine of the kind described, a channeling member, a forming device trailed after said channeling member, means to introduce traffic line material in rear of said channel

member and at the front portion of said forming device, and fingers pivotally carried by said channeling member and having down-turned free ends spaced from the rear end of said channeling member and extending down and into the concrete below the base line of the channel formed by said channeling member.

5

JOHN N. HELTZEL.
